UNITED STATES PATENT OFFICE.

PHILIPP KOSTER, OF FRANKFORT-ON-THE-MAIN, GERMANY.

AUTOMATICALLY-UNSLAGGING SHAFT CONSTRUCTION FOR WATER-GAS GENERATORS.

1,400,885.

Specification of Letters Patent. Patented Dec. 20, 1921.

Application filed October 2, 1915. Serial No. 53,781.

(GRANTED UNDER THE PROVISIONS OF THE ACT OF MARCH 3, 1921, 41 STAT. L., 1313.)

To all whom it may concern:

Be it known that I, PHILIPP KOSTER, a citizen of the German Empire, residing at Frankfort-on-the-Main, in the Province of 5 Hessen-Nassau and State of Prussia, Germany, have invented certain new and useful Improvements in Automatically-Unslagging Shaft Constructions for Water-Gas Generators, for which I have filed an application in Germany on November 9, 1914, and I hereby declare that the following is a full, clear, and exact description thereof, reference being had to the accompanying drawings, which form part of this specification.

15 This invention relates to water-gas producers in which an automatically unslagging shaft with a basket-like grate having a central unslagging opening is employed.

The employment of a basket-like grate in 20 connection with water-gas producers as heretofore constructed, whereby the unsafe and expensive mechanical turning of the grates is avoided, presents a series of difficulties which are overcome by an advantageous arrangement such as hereinafter 25 described and shown in the accompanying drawings.

What has been very easy with generators for producing generator gas has proven very 30 difficult with water-gas generators. With generator-gas producers the question is one of continuous working, whereas with water-gas producers it is a question of periodical working. In generator gas producers a uniform air current, or air and steam current, 35 travels through the generator always in the same direction, that is, from above to below and the steam admitted cools the turning grate, while the air supplied absorbs the 40 carbon from the fuel, so that on the turning grate slags only are left, which owing to the steam supplied, are cooled and broken into easily broken pieces. The pressure in such generators is also low and always uniform.

45 In the interior of the turning grate air only is present, so that the cavity beneath the turning grate can be kept large without the danger of explosion, which might otherwise result. In the operation of water gas producers the pressure in the generator changes 50 from 24 to 30 times per hour, for instance, the pressure is at 0 when filling the generator, and is from 500 to 600 millimeters during the sharp blowing, and again at 0

when changing from blowing to gassing and 55 from 150 to 250 millimeters during the gassing (depending on the retort pressure and working of the generator), and again at 0 when changing from gassing to blowing, and when blowing the pressure increases again 60 to its maximum, which at the change of an incomplete gassing out, results frequently in ignition, that is, in small explosions below the grate, so that a pressure of 800 or more millimeters is momentarily attained. 65 When filling the generator with fresh coke the pressure again falls to 0. These frequent changes of pressure, which lie within wide limits, aggravate the employment of water seals, that is, of divings, for in the 70 first place, the diving for each seal must amount to about one meter water column to insure a safe working, and secondly, the vessels must be of such dimensions that an eventual water ejection caused by the rapid 75 high pressure vibrations will not result in working interruptions, and with such high diving it is difficult to remove the slag from the turning cup of the turning grate. With an ordinary generator gas producer with 80 low diving, the slag travels automatically over an inserted inclined slide out of the cup, in order to fall into the slag truck placed beside the latter. With water gas production with high diving in the turning 85 cup the slag will not automatically travel up the inclined plane, but must be raised from the cup bottom by an elevator, helix or the like, and consequently the high column causes great friction and quick wear of 90 the turning grate and operating mechanism, and even small disturbances result in interruptions and in cumbersome, expensive and time-wasting repairs. In order to avoid such difficulties in the employment of turning 95 grates, the dry turning grate has been employed instead of the wet turning grate formerly used, but the latter has resulted in still more dangerous difficulties for the water-gas producer. The inconvenient removal of the slag is avoided by this construction, but a soiling of the lower part 100 of the cavity of the turning grate takes place which is very dangerous for the water gas producer to which there is no access from 105 the outside, and necessary repairs result again in great disturbances. The most dangerous feature in the operation of the dry

turning grate, however, is the increased danger of explosion in the large turning grate cavity and in the still more dangerous lower cavity. When blowing, the turning 5 grate cavity is filled with air, and part of this air, mixed with small quantities of generator gas, flows for a pressure balance, through the slag layer into the lower cavity beneath the turnable slag cup. When chang- 10 ing from blowing to gassing the pressure in this lower cavity at first falls to 0, and it is then refilled with good water gas, which, as it travels through the coke column in a direction from above to below, passes into 15 the large turning grate cavity in order to flow from thence through the lower gas outlet (which at the same time is also an air inlet) to the scrubber. Owing to the pressure distance from 0 to 200 or to 250 milli- 20 meters water column, the corresponding quantity of water gas also flows into the lower cavity beneath the turning cup and forms with the air mixture therein an explosive gas mixture which at any time dur- 25 ing the change of working, owing to the escap- 30 ing of the gases by the pressure balance, might cause ignition of these gases at the glowing coke layer, and eventually cause bad explosions in the lower part of the turning 35 grate. Even the best turning grate constructions in water gas producers offer a drawback since the slag removed frequently leaves the generator mixed with much coke which naturally makes the unslagging proc- 40 ess a very uneconomic one. There is again a difference between the continuously working generator gas producer and the periodical working gas producer. The working of the latter is frequently interrupted for a 45 longer time, as the water gas consumption is variable and a small gas container only is available for the reception of the water gas produced. The attendant effects as many rapid consecutive sharp blowing and gassing 50 periods as necessary for filling the gas container, in spite of the permanent consump- 55 tion. Then he interrupts the working for a certain time in order to again feed the generator with the required quantity of coke or 60 to do other impending work so that the gas container has again fallen so far that it again needs quick attention. An automatically running turning grate will not easily adapt itself to these frequent changes of 65 working. Besides, the coke which is mixed with the slag has slipped so far down the turning grate that the air can not touch it and its utility in the generator is lost. Owing to the above described difficulties con- 70 nected with the employment of a turning grate, the cumbersome unslagging operation by hand has hitherto been preferred in connection with water gas generators. For this purpose an auxiliary grate consisting 75 of single strong flat iron bars are driven

into the generator through the opened slag doors at the uppermost point of the latter, and this auxiliary grate was provided to keep the good coke in a raised position, when the slag and the intermixed coke was pulled 80 out of the generator between the grate and the auxiliary turning grate. Thus, the grate could again be cleaned from any slag, but this cleaning required from half an hour to an hour, depending upon the size of 85 the generator. Furthermore, the work connected therewith was cumbersome, and the attendance of from four to six men was required for the unslagging operation, whereas the attendance upon a generator as described in the present invention requires only one man. Further, during the removal process large deposits of coke would be removed along with the slag, and must be either lost with the slag or must be separated from it and again fed to the generator. After each of these unslagging processes the coke layer in the generator would fall considerably; the missing column, which was taken out of the generator between the auxiliary grate and the grate, must be replaced by refilling, which again was a time waste. In the present invention, an automatically unslagging shaft for water gas producers is obtained by connecting the central unslag- 90 ging opening of a stationary annular basket-like grate with the upper edge of the diving pipe inserted in the conically protuberant shaft bottom, by means of a connection pipe provided with rather wide interstices. The most important advantage 95 of this construction is the economic utilization of all the coke which is fed into the generator. The escaping slag which generally intermixes with considerable quantities of coke falls in the connection pipe between the central opening of the basket-like grate and the upper edge of the diving pipe and comes in touch with the fresh incoming oxygen of the blowing air, and is 100 safely burned, the heat produced being utilized in the generator. The hot blown coke- 105 rest, in the slag, falls off from decomposition, when touched by the steam flowing into the generator below the grate so that the steam burns the last glowing coke rests out of the slag for the water gas formation. At 110 the same time, by the working of the slag and ashes the bulk of the latter is reduced so that its removal is facilitated. The construction has the further advantage that the noxious space beneath the grate becomes as small as it could hitherto be obtained with the normal water gas generator only, so 115 that neither explosions can take place nor a bad water gas be produced by soiling with nitrogen. With turning grate generators it was hitherto not yet possible to reduce the large noxious cavities. Further, by reason 120 of the existing mud, the danger of water 125 130

coming in too close relation with the steam, the glowing coke, or the gas to be formed, is advantageously avoided. Furthermore when gassing from below to above the steam 5 below the grate is kept from coming in touch with cold iron bars, a result which was otherwise unavoidable with turning grates, and caused vigorous condensed water formations and an uneconomic steam 10 consumption. This construction has, further, no sensitive parts, and permits the removal of the slag masses through the interstices of the connection pipe by means of slagging tools and without requiring any 15 interruption in the working. My invention is illustrated in the accompanying drawing which represents an appropriate form of construction.

Figure 1 shows the shaft in a longitudinal 20 section, and

Fig. 2 is a cross section of the same.

1 and 2 represent the channels for the introduction of air or steam, or for leading off the effective gas and are each connected with 25 steam supply pipes 8 and 9, and also with gas leading off pipes 5 and 6, the channel 1 being further a blast and chimney opening. 10 represents a fire door; 11 a basket-like grate; 12 a conically shaped shaft bottom; 30 13 a diving pipe; 14, mud, and 15 a slag removing device. In the present invention, between the upper edge of the diving pipe 13 and the lower edge of the basket-like grate 11, a connection pipe 16 is arranged 35 which is provided with large interstices, 17 is a slag door. The operation of the invention is as follows:

The air is pressed from the air pipe 7 through the channel 1 beneath the basket-like grate and escapes in products of combustion from the shaft through the chimney opening. After blowing, the air valve of the air pipe 7 and chimney opening 3 are closed and steam is supplied through pipe 8 45 into the channel 1. The steam circulates through the grate and the whole coke column and leaves a shaft in the form of water gas through the channel 2 and passes through the valve 4, thence to the main gas 50 valve 6. After the gassing and closing of the steam pipe 8 and of the gas valve 4, the chimney 3 is reopened and air is supplied from the pipe 7 through the channel 1, as before. After the heating of the coke and 55 the closing of the air valve in the pipe 7 and of the chimney 3, steam is then driven from above through the channel 2 and through the coke column, and the finished water gas penetrates the basket-like grate in 60 order to pass through channel 1, through the valve 5, and then to the main gas pipe 6. The slag formed during this working slips on the inclined basket-like grate to its deep-

est point and falls thence through the central opening into the space between the grate 65 11 and shaft bottom 12 from which point it again falls through the diving pipe 13 into the mud 14. The inclination of the basket-like grate 11 must of course be such that the slag formed on the grate moves automatically toward its bottom opening. Consequently, that part of the slag layer which lies between the basket-like grate 11 and the diving pipe comes into effective touch with steam and air and is thoroughly freed from 70 75 any coke-rests.

Without departing from the spirit and scope of my invention it can be put into practice in the following manner. Instead of a separate connection pipe the basket-like 80 grate can be provided with a cylindrical or conical grate-like extension. Furthermore, between the opening of the basket-like grate 11 and the upper edge of the diving pipe 13, a free space through which steam and air travel, may be created in such a way that the supporting tube 16 can be entirely omitted. In this case the basket-like grate must be so constructed that the free spaces can be maintained therein by the proper spacing 90 of the basket, or by some other means.

What I claim is:

1. A furnace for the production of water-gas comprising a shaft having a feed opening in its upper end and a conically-shaped 95 bottom having a centrally disposed opening therethrough, a diving pipe depending from said opening, a basket-like grate supported above the shaft bottom and having a central opening therethrough of smaller size than 100 the opening in said shaft bottom, and an annular grate-like connection between said shaft bottom and basket-like grate surrounding said openings and enlarging toward the opening in the shaft bottom. 105

2. In combination with a shaft furnace for the production of water-gas having a conically-shaped bottom, a basket-like grate supported above said bottom, a combined valve-controlled air and steam inlet and gas 110 outlet pipe opening into said shaft between said conically-shaped bottom and basket-like grate, a valve-controlled steam inlet and gas outlet pipe opening into the upper part of said shaft, and a valve-controlled pipe 115 connected with said combined inlet and outlet pipes for carrying off the gas as it issues alternately through said pipes.

In testimony that I claim the foregoing as my own I affix my signature in presence of 120 two witnesses.
